BIASED PAWL

James P. Watson, Inglewood, Calif. (59 Waterway Road, Waterway Village, Jupiter, Fla.), assignor of one-half to Joe Davidson, South Gate, Calif.

Original application May 6, 1958, Ser. No. 733,449, now Patent No. 2,933,580, dated Apr. 19, 1960. Divided and this application Nov. 17, 1959, Ser. No. 853,632

6 Claims. (Cl. 74—577)

This application relates to pivotally balanced members, and more particularly such members as are used in stepping switches and motors.

This invention relates to improvements in pivoted components of the type disclosed in co-pending applications Serial No. 607,422 (now issued as Patent No. 2,866,109) and Serial No. 662,109, both filed in the name of James P. Watson. This application is a division of copending United States patent application Serial No. 733,449 filed May 6, 1958, now Patent No. 2,933,580 entitled "Pivotally Balanced Members."

It is an object of this invention to provide an improved balanced pawl structure.

It is a further object of this invention to provide a pawl structure which is easier and cheaper to manufacture and assemble and which has increased longevity as compared with prior art structures of this general type.

It is another object of this invention to provide a design for a resiliently biased pivoted pawl structure wherein a heavier spring wire may be used without proportionate increase in biasing torque, thereby permitting use of stronger and longer lived spring components.

It is another object of this invention to provide a spring biased rotary balanced pawl wherein the biasing spring is free to perform its rotary bias on the pawl without being required to absorb an axial force to restrain the pawl in place on its mounting pin.

It is another object of this invention to provide a balanced, biased pawl wherein consistent operation may be obtained without maintenance of critical structural tolerances.

In accordance with these and other objects which will become apparent hereinafter, preferred forms of the present invention will now be described with reference to the accompanying drawings, wherein:

Fig. 1 is a perspective view illustrating the balanced pawl of the present invention;

Fig. 2 is a section taken on line 2—2 in Fig. 1; and

Fig. 3 is a section taken on line 3—3 in Fig. 1.

Referring now to Figs. 1-3, the balanced pawl of the present invention will now be described. This pawl is generally of the type described in said United States Patent 2,866,109, particularly at Figs. 11-14, and in said Serial 662,109, particularly at Figs. 6-10. Reference to these specifications is hereby made for a fuller understanding of the environment in which the pawl shown in Figs. 1-3 is employed.

Referring to these figures, 71 designates an arbor or pin forming a bearing for a pawl 72. The bearing portion of the pin 71 is ensmalled as shown at 73 where it passes through a bore (not shown) in the pawl 72, leaving a head 74 which restrains the pawl 72 against axial movement on the pin 71 in one direction. The pawl is prevented from moving axially in the other direction by bearing against a suitable mounting member (not shown) in which the pin 71 is mounted. The head 74 of the pin 71 has a pair of axially spaced circumferential grooves 76 and 77. A diametral slot or kerf 78 is also provided

2

in the head, and the slot 78 has a sloping floor or bottom 79 communicating between the grooves 76 and 77.

A spring wire 81 engages the pin 71 and pawl 72 to rotatively bias the pawl, in the following manner. The 5 central portion 82 of the wire 81 resides in the slot 78 adjacent the floor 79 thereof, the respective ends of the wire 81 are then wrapped around the pin 71 in the same rotative direction, residing in the respective circumferential grooves 76 and 77. Thus, one end of the wire 81 emerges from the shallow end of the kerf or slot 78 and proceeds around the groove 76 as shown at 83 through an arc of approximately 270° and then leaves the groove 76 tangentially as shown at 84. The tip 86 of the wire is then engaged in a notch or pocket 87 formed in a lateral post 88 at one end of the pawl 72. The notch or pocket 87 is in substantial alignment with the circumferential groove 76 so that the spring wire 81 may proceed directly from the pin 71 to the pocket 87 without further bending. This obviates canting of the spring ends with 15 consequent danger of chafing.

The opposite tip 91 of the wire 81 resides in a pocket or notch 92 formed in a post 93 at the opposite end of the pawl 72, which faces oppositely from the pocket 87. The pocket 92 is spaced transversely of the pocket 87 25 so as to lie in substantial longitudinal alignment with the other circumferential groove 77 from which the tip end 91 emerges. This end is thus likewise prevented from canting and chafing.

That portion of the head 74 between the groove 77 30 and the pawl 72 constitutes a flange 94 which serves to hold the pawl 72 against axial removal from the pin 71.

The flange 94 obviates requiring the spring wire 81 to hold the pawl 72 against axial removal from the pin 71, consequently decreasing the loading on the spring and 35 eliminating chafing. The large wrap-around of approximately 270° provided for each end of the spring 81 permits the use of heavier spring wire and also makes the positioning of the kerf 78 much less critical than if the extensive wrap-around were not employed.

40 While the instant invention has been shown and described herein in what is conceived to be the most practical and preferred embodiments, it is recognized that departures may be made therefrom within the scope of the invention which is therefore not to be limited to the details disclosed herein but is to be afforded the full scope 45 of the claims.

What is claimed is:

1. Balanced pawl means comprising a pawl having first and second end portions, a pivot pin projecting through 50 said pawl at the center thereof, said pin having a pair of spaced circumferential grooves and a diametral slot communicating from one groove to the other, and a spring wire having its central portion residing in said slot, the respective ends of said spring each being wrapped in a 55 respective one of said grooves in the same rotative direction through an arc of substantially more than 180° and extending from the respective grooves in the direction of respective ones of said first and second end portions, the tips of said spring wire engaging the respective end portions of said pawl to rotatively bias said pawl in a given 60 rotative direction.

2. Pawl means in accordance with claim 1 wherein said pawl is provided with pockets at each of said end portions thereof in which the respective ends of said wire 65 reside.

3. Pawl means in accordance with claim 1 wherein said pawl is provided with pockets at each of said end portions thereof in which the respective ends of said wire reside and wherein said pockets are spaced longitudinally 70 and transversely of one another and lying in substantial longitudinal alignment with the respective grooves from

which the wire ends extend, thereby to obviate canting of said spring ends with consequent chafing thereof.

4. Pawl means in accordance with claim 1 wherein said spring wire resides in the respective circumferential grooves through an arc of at least approximately 270°.

5. Pawl means in accordance with claim 1 wherein that portion of the pivot pin passing through said pawl is enameled leaving a flange on said pin adjacent said pawl which inhibits axial movement of said pawl along said pin in one direction.

6. Balanced pawl means comprising an elongated pawl having first and second end portions with pockets formed in each of said end portions, a pivot pin projecting through said pawl at the center thereof wherein that portion of the pivot in passing through said pawl is of a reduced diameter forming a shoulder on said pin adjacent said pawl which inhibits axial movement of said pawl along said pin in one direction, said pin having a pair of spaced circumferential grooves and having a diametral

slot communicating from one groove to the other, and a spring wire having its central portion residing in said diametral slot, the respective ends of said spring each being wrapped in a respective one of said grooves in the same rotative direction through an arc of at least approximately 270 degrees, the tips of said spring wire residing in respective ones of said pockets to respectively bias said pawl in a given rotative direction, said pockets being spaced longitudinally and transversely of one another and lying in substantial longitudinal alignment with the respective grooves from which the wire ends extend, thereby to obviate canting of said spring ends with consequent chafing thereof.
